UNITED STATES PATENT OFFICE.

RUSSELL W. PERKINS, OF WEST MERIDEN, ASSIGNOR TO HIMSELF AND
JAMES H. HOLMES, OF WALLINGFORD, CONNECTICUT.

DESIGN FOR A WORK-HOLDER.

Specification forming part of Design No. 6,191, dated March 11, 1873.

To all whom it may concern:

Be it known that I, RUSSELL W. PERKINS, of West Meriden, in the county of New Haven and State of Connecticut, have invented a new Design for Work-Holder; and I do hereby declare the following, when taken in connection with the accompanying photographic illustration, to be a full, clear, and exact description of the same, and which said illustration constitutes part of this specification, and represents a perspective view.

This invention relates to a design for that class of work holders in which the work is clamped between a swinging cam and the base; and it consists in the figure of a sailor standing upon a base, apparently leaning against an anchor, the anchor pivoted to the figure, and

swinging so that the anchor forms the clamping device for the holder.

On a base, of any desirable form, stands the figure of a sailor, and beside him is an anchor, the figure apparently leaning against the anchor, the arms of the anchor down upon the base, the anchor being pivoted to the figure at the point where the two come together so that the anchor will swing back and forth.

I claim as my invention—

The design for work-holder, as herein described and shown in the accompanying illustration.

RUSSELL W. PERKINS.
